UNITED STATES PATENT OFFICE.

FRANK W. SIGOURNEY, OF BRISTOL, CONNECTICUT.

DESIGN FOR A BULLETIN-BOARD.

SPECIFICATION forming part of **Design No. 24,885**, dated **November 12, 1895**.

Application filed September 27, 1895. Serial No. 563,910. Term of patent 3½ years.

To all whom it may concern:

Be it known that I, FRANK W. SIGOURNEY, of Bristol, in the county of Hartford and State of Connecticut, have invented and produced a new and original Design for a Bulletin-Board, 5 of which the following is a specification.

The figure of the drawing, forming a part of this specification, represents my design in perspective in the form of an easel.

10 The leading features of my design consist of a plain blackboard-surface bordered by a contrasting surface, the border-surface above the blackboard-surface being ornamented with a clock and a thermometer, and the outer line of the said upper border-surface being 15 irregular and extending in ornamental curved or scroll lines.

In the drawing, *a* designates the plain blackboard-surface.

20 *b* designates the side bordering surface. *c* is the bottom bordering surface, and *d* the upper bordering surface.

The bordering surfaces are in contrast to the sense of sight with the central surface *a*. The upper bordering surface *d* is ornamented 25 on its face with a clock *e* and a thermometer *f*, and its outline *g* is extended on ornamental curved or scroll lines, as shown. I may also, though it is not essential, ornament the upper bordering surface with contrasting circular surfaces *h* or surfaces or figures of different forms.

What I claim is—

25 The design for a bulletin board as herein shown and described.

In testimony whereof I have signed my name to this specification, in the presence of two subscribing witnesses, this 20th day of September, A. D. 1895.

FRANK W. SIGOURNEY.
